UNITED STATES PATENT OFFICE.

GEORGE E. GOUCHE, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,893, dated May 8, 1883.

Application filed February 8, 1883. Term of patent 14 years.

To all whom it may concern:

Be it known that I, GEORGE E. GOUCHE, a citizen of the United States, residing in the city and county of Philadelphia, and State of Pennsylvania, have invented and produced a new and original Design for Fringe, of which the following is a specification, reference being had to the accompanying drawings, forming part thereof.

10 Of the drawings, Figure 1 is a front elevation of a fringe embodying my design. Fig. 2 is a cross-section of the pendant.

15 In the drawings, A are pendants, each of which is of the form of an octagonal parallelopipedon, ornamented with balls B, and attached to any suitable heading, C.

I claim--

1. A design for a fringe, consisting of a heading, and of pendants of the form of an octagonal parallelopipedon, as shown and described. 20

2. A design for a fringe, consisting of a heading, and of pendants of the form of an octagonal parallelopipedon ornamented with balls, as shown and described.

In testimony whereof I have hereunto signed 25
my name this 29th day of January, A. D. 1883.

GEORGE E. GOUCHE.

In presence of—

J. BONSALL TAYLOR,
JOHN JOLLEY, JR.
